UNITED STATES PATENT OFFICE.

JOHN HOUPT, OF SPRINGTOWN, PENNSYLVANIA.

COMBINED FEED-PUMP AND CONDENSING APPARATUS FOR ENGINES.

SPECIFICATION forming part of Letters Patent No. 296,009, dated April 1, 1884.

Application filed January 10, 1884. (No model.)

To all whom it may concern:

Be it known that I, JOHN HOUPT, of Spring-
town, in the county of Bucks and State of Penn-
sylvania, have invented certain new and use-
ful Improvements in Combined Feed-Pumps
and Condensing Apparatus for Engines, of
which the following is a full, clear, and exact
description.

This invention more especially relates to
combined feed-pumps for steam-boilers of
marine engines, and condensing apparatus for
supplying hot fresh water thereto; and it em-
braces, subject to certain modifications or ad-
ditions, the compound condensing apparatus
for which Reissued Letters Patent of the United
States No. 8,670 were granted me April 15,
1879, and the compound-plunger feed-pump
for which Letters Patent No. 285,622 were
issued to me September 25, 1883. The con-
densing portion of the combined apparatus
comprises a primary condenser or moderator,
by means of which the exhaust-steam from the
steam-cylinder of the engine is cooled to a tem-
perature a little below that of boiling water,
(under a partial vacuum,) to moderate the
temperature and rush of the exhaust-steam
from the steam-cylinder on its way toward a
secondary condenser, and, by retaining a com-
paratively low temperature in the said sec-
ondary condenser, operating to produce a
good vacuum in front of the piston of the en-
gine, and to keep up a higher temperature in
the steam-cylinder than can be practically af-
forded by the ordinary condensing steam-en-
gine, substantially as described in my said Re-
issued Letters Patent No. 8,670, April 15, 1879,
and in which apparatus, as there described,
pipes are arranged to connect the primary
condenser with a hot-well below, and with the
secondary condenser, an air-pump being con-
nected with the hot-well, from which hot water
may be supplied to any number of steam-boil-
ers, and a circulating-pump being connected
with the condensers. Combined with this con-
densing apparatus is the compound-plunger
force-pump, having a pipe-connection there-
with, controlled by a cock or valve for open-
ing or closing connection, as required. When
it is desired to supply the steam-boilers with
hot fresh water at a higher temperature than
could be afforded by the ordinary condenser,
and thus also economize fuel, said cock is

opened and the force-pump is operated, where-
by a large portion of the hot water of condensa-
tion from the primary condenser may be drawn 55
off and be forced either directly into the hot-
well or into the steam-boilers without allow-
ing it to pass through or interfere with the air-
pump, while the hot vapor from the primary
condenser will be drawn by the air-pump into 60
the secondary condenser or save-all, and there
be condensed to save the remnant of fresh-
water for supplying the boilers, and to pro-
duce the desired effect in front of the engine-
piston. This compound-plunger force-pump 65
may be the same as that described in my here-
inbefore-referred-to Letters Patent No. 285,622;
but it is preferred to arrange its elongated
plungers to work both from below or the same
side, and so that they will perform their strokes 70
simultaneously in opposite directions, which
arrangement will be found much more con-
venient, and the plungers be made to balance
each other on opposite sides of the axis of an
actuating-beam or other device. Such, or it 75
might be a differently-constructed force-pump,
may be applied for use in connection with the
condensing apparatus as described. I further
connect with the condensing apparatus or sec-
ondary condenser thereof, subject to control 80
by a cock, an upwardly inclining or ascend-
ing pipe, for drawing off the accumulated hot
vapor from the force-pump, by the action of
the air-pump, whereby I am enabled to utilize
said hot vapor, instead of allowing it to become 85
an annoyance to other parts, and whereby back-
pressure on the receiving-valves of the pure
hot water force or feed pump is equalized and
overcome.

Reference is to be had to the accompany- 90
ing drawing, in which the figure represents a
vertical section of a combined feed-pump and
condensing apparatus embodying my inven-
tion.

R indicate the primary condenser or mod- 95
erator, which is here shown double, and as
having surface-condensing cases, which are
connected, as at a, with the exhaust pipes or
branches of the engine-cylinder, and with
which are connected pipes r' r'', communicat- 100
ing with the hot-well W below.

S is the secondary condenser or save-all, the
upper portion of which communicates by a
pipe, r'', with the pipe r', and its lower portion

with the pipe r'' , and whereby the primary condenser or condensers are directly intermediate of the steam-cylinder and secondary condenser or save-all.

5 T represents the air-pump; U the hot-well, V the hot-water-supply pipe for boilers, and Z the circulating-pump, all combined for operation substantially as hereinbefore referred to, and described in my Reissued Letters Patent No. 8,670, herein previously mentioned, and for the purposes specified.

The condensers R R and S may either be of the description shown in the drawing, or of any other suitable construction. The exhaust steam enters the primary condenser R R, where it will be cooled to a temperature below that of boiling water, (under a partial vacuum,) and the hot water of condensation be caused to drop and pass off through the pipes $r' r''$ into the hot-well W, from whence it is drawn by the air-pump T, and forced into the hot-well U for supplying the steam boiler or boilers with hot fresh water. To the left of the figure is shown the force or feed pump for supplying the steam-boilers with hot fresh water at a higher temperature than could be afforded by the ordinary condenser, and whereby a large portion of the hot water of condensation from the primary condenser may, when desired, be drawn off and forced directly into the hot-well U, or into the steam-boilers, without allowing it to pass through or interfere with the air-pump T. This force or feed pump is attached by a pipe, M, to the pipe r' , intermediate of said pipe r' and the pipe r'' . This connection M, through which the hot fresh water is drawn by the force-pump, is provided with a cock, P, for regulating or establishing or closing connection with the condensing apparatus, as required. Said force or feed pump, as represented in the drawing, is a compound or double plunger one, similar in its general construction to that described in my Letters Patent No. 285,622, hereinbefore referred to, but in which the elongated plungers B J, instead of being worked one from above and the other from below, and made to move simultaneously in the same direction, are arranged to be worked both from below or the same side, and to move simultaneously in opposite directions, which is a more convenient arrangement generally, and provides for a balancing action of the plungers, and readier operation of them, as hereinbefore specified.

55 A indicates the cylinder of the feed-pump proper, and B its elongated plunger.

C is the delivery-valve of the pump, arranged at the upper or discharge end of the cylinder A, within or under cover of an outlet branch, D.

E E' indicate the hot-water-supply pipe or passage to the upper or discharge end of the cylinder A from the cylinder F of the auxiliary pump or plunger J, said passage being made within a removable plug, H, and being fitted with a spring check-valve, G.

The inlet-valve of the auxiliary pump is indicated by the letter L.

The two plungers B J serve to keep up a constant supply of hot fresh water supplied by condensation from the primary condenser and force it into the boiler or boilers, as hereinbefore described, the cock P being opened for the purpose.

Connecting the cylinder F, subject to control by a cock, N, with the upper end of the secondary condenser S or pipe r'' , leading thereto, is an upwardly inclining or elevating pipe, O, for drawing off the accumulated hot pure vapor from the compound-plunger pump by the air-pump T of the compound condensing apparatus, and thereby utilizing said hot vapor, instead of allowing it to become an annoyance in equalizing and overcoming back-pressure on the receiving-valves of the compound pure-hot-water feed-pump.

Having thus described my invention, I claim as new and desire to secure by Letters Patent—

1. In condensing and boiler-feeding apparatus for steam-engines, in which a primary and a secondary condenser are used, the combination, with the primary condenser or moderator for direct application to or connection with the engine-cylinder, and arranged intermediately of said cylinder and the secondary condenser, and with a feed or force pump in controllable connection with the duct which passes off the hot water of condensation from the primary condenser, of a pipe or duct in controllable connection with said force or feed pump and with the secondary condenser, for drawing off accumulated hot pure vapor from the pump, substantially as specified.

2. The combination of a compound condensing apparatus in which a primary condenser or moderator and a secondary condenser are used, and a compound plunger, force, or feed pump adapted to supply to the boiler or boilers of an engine hot fresh water of condensation from the primary condenser, essentially as and for the purposes herein set forth.

3. The combination, with the pipes M O and valves L N P, with the pump barrel or chamber F, of a compound-plunger pump, the primary condenser or moderator R R, pipes $r' r''$, the secondary condenser or save-all S, the air-pump T, and hot-well W below, substantially as shown and described.

4. In a combined condensing and boiler-feeding apparatus, the combination, with the cylinder A of the pump, the elongated plunger B, and the outlet and check valves C G, of the auxiliary pump-cylinder F, elongated plunger J, and valve L, the plungers B and J being adapted both to work from the same side of the pump, and to make their strokes simultaneously in opposite directions, essentially as specified.

JOHN HOUPT.
